(57) CLAIM

The ornamental design for a snow globe soap bottle, as shown and described.

DESCRIPTION

FIG. 1 is a front side elevation view of a snow globe soap bottle embodying our new design in which the particles are settled; and,

FIG. 2 is a front side elevation view thereof in which the particles are suspended some time after agitation, in which the particles partially obscure the candy cane.

There are no top, bottom, left, right, or rear elevational views, as the ornamental features of the design are either not claimed or not seen from those perspectives.

The broken line showing is for illustrative purposes only, and forms no part of the claimed design.
